[57] CLAIM

The ornamental design for a table grill, as shown and described.

DESCRIPTION

FIG. 1 is a perspective view of a table grill showing my new design;

FIG. 2 is a top plan view thereof;

FIG. 3 is a left end elevational view thereof, the right end being a mirror image thereof;

FIG. 4 is a front elevational view thereof; and,

FIG. 5 is a rear elevational view thereof.

The bottom of the pan thereof is plain and unornamented.

The appearance of the portion of the article shown in dashed lines does not form a part of the design.
